ATTACHMENT FOR FELT CONDITIONERS

Filed Nov. 24, 1926

By Clarence A. O'Brien,
Attorney

UNITED STATES PATENT OFFICE.

WILLIAM RILEY FOWLER, OF HAMILTON, OHIO.

ATTACHMENT FOR FELT CONDITIONERS.

Application filed November 24, 1928. Serial No. 150,561.

The present invention relates to an attachment for a felt conditioner such as is used in a paper-making machine. These conditioners are subjected to considerable wear at the top surfaces thereof. It is the present practice to discard a conditioner when the top surface thereof has become excessively worn. The object of the present invention is to provide a new top surface in the form of an attachment, thus eliminating the great waste which is occasioned by the discarding as junk of the worn felt conditioners.

Another very important object of the invention lies in the provision of an attachment of this nature which may be manufactured at a low cost and yet will prove thoroughly efficient and reliable in use and well adapted for the purpose for which it is designed.

With the above and numerous other objects in view, as will appear as the description proceeds, the invention resides in certain details of construction as will be herein-after more fully described and claimed.

In the drawing:

Figure 1 is an elevation of a felt conditioner suction box with my improved attachment thereon,

Fig. 2 is a top plan view thereof,

Fig. 3 is a perspective view of the attachment showing the same inverted,

Fig. 4 is a detail sectional view taken substantially on the line 4-4 of Fig. 2.

Referring to the drawings in detail it will be seen that 5 denotes generally a well known type of felt conditioner suction box now in quite common use. The upper surface of this conditioner is subject to considerable wear as is well known and heretofore it has been the custom to discard the conditioner after the wear has become excessive. In order to eliminate this waste, I have devised an attachment in the form of an oblong plate 6 substantially rectangular in formation and provided with a longitudinally extending slot 7 at one end and a pair of openings 8 adjacent the other end, said openings and said slots being disposed along the median longitudinal dimension of the plate.

On the under surface of the plate along the side edges thereof I provide ribs 9 the inner surfaces of which are dove-tailed.

On said under surface of the plate I also provide a transverse rib 10 along that end

adjacent the slot 7. This plate takes the place of the worn surface on the conditioner. It will be apparent that the plate may be readily slid longitudinally over the surface and the dove-tailed ribs 9 will engage flanges 11 formed on the worn upper wall of the conditioner, as is clearly shown in Fig. 4. At one end the plate 6 is provided with a pendent flange 8^x, the said flange 8^x constituting a convenient handle or finger piece for the positioning or the removal of the plate 6.

The attachment is essentially a renewal part and has for its purpose to prevent the throwing away of the felt conditioner suction box when the top surface thereof is worn, this attachment simply slips over the worn-out surface and thus enables the felt conditioner to be used again, instead of being thrown away as is now the custom.

As will be understood by comparison of Figures 1, 3 and 4, the worn-out box 5 can be machined with a taper slightly wider at one end than the other, and dove-tailed to receive my novel plate 6 which is machined slightly wider at one end than at the other and is also dove-tailed so as to slip on the box 5 and be air tight without the employment of screws or other fastenings or extraneous means of any kind. It will also be understood that when machined as stated, the plate 6 is susceptible of being switched on and off without the assistance of any tools whatsoever.

The oblong slot 7 in the plate 6 is for suction purposes to hold the felt belt on the fluid ejecting element 12, the steam ejecting element 13, and the brush 14, the said slot 7 being arranged in coincidence with said element as illustrated in Figure 2. The apertures 8 are suction ports for the removal of any dirt that is brushed off the felt belt by the brush 14.

It is thought that the construction operation and advantages of this invention will now be clearly understood by those skilled in this art without a more detailed description thereof. The present embodiment of the invention has been disclosed in detail merely by way of example since in actual practice it attains the features of advantage enumerated as desirable in the statement of the invention and in the above description. It will be apparent, however, that changes in the details of construction, design, and the like may be resorted to without departing from the spirit

or scope of the invention as hereinafter claimed or sacrificing any of its advantages.

Having thus described my invention what I claim as new is:

1. In means for the purpose described, the combination with a box opened at its upper side and machined so as to have a taper and to be wider at one end than at the other, and being dove tailed, of an apertured plate machined with a taper so as to be wider at one end than the other and dove-tailed and adapted to be slipped endwise on the box and be tightly held to the box in air tight manner of itself.
2. In means for the purpose described, the combination with a box opened at its upper side and machined so as to have a taper and to be wider at one end than at the other, and being dove tailed, of an apertured plate machined with a taper so as to be wider at one end than the other and dove-tailed and adapted to be slipped endwise on the box and be tightly held to the box in air tight manner of itself; the said plate being equipped at one end with a pendent portion constituting a hand hold or finger piece.
3. In means for the purpose described, the

combination with a box open at its upper side and machined to have a tapered upper portion of a greater width at one end than at the other, said portion being dove-tailed, fluid ejecting means, steam ejecting means and a brush in said box, of a plate having a slot in coincidence with said fluid ejecting means, steam ejecting means and brush and also having a suction port, said plate being machined and dove-tailed in conformity with the box and adapted when slipped endwise on the box to fit the box in an air-tight manner.

4. In means for the purpose described, the combination with a box open at its upper side and flanged and dove tailed, fluid ejecting means in the box, steam ejecting means also in the box and a brush in the box, of a plate having a pendent dove-tailed flange whereby it may be slid into engagement with and be held of itself on the box and having a slot in coincidence with said fluid and steam ejecting means and said brush and also having a suction port.

In testimony whereof I affix my signature.

WILLIAM RILEY FOWLER.
